UNITED STATES PATENT OFFICE.

WILLIAM C. FREE, OF ROCKFORD, ILLINOIS.

SEWING-MACHINE.

1,245,212.

Specification of Letters Patent.

Patented Nov. 6, 1917.

Application filed August 7, 1915. Serial No. 44,235.

To all whom it may concern:

Be it known that I, WILLIAM C. FREE, a citizen of the United States, residing at Rockford, in the county of Winnebago and 5 State of Illinois, have invented certain new and useful Improvements in Sewing-Machines, of which the following is a specification.

My invention relates more particularly to 10 the support, table or cabinet of the machine. Prior to my invention sewing machines have ordinarily been mounted on a cast metal frame which supports a table top upon which the sewing machine head is permanently mounted. It has also been common 15 prior to my invention to so mount the head of the machine upon a pivoted or reciprocating support, that it may be concealed within the frame when not in use, and a pivoted 20 leaf has been combined with such a movable support so that when the leaf is swung outward or extended to one side of the table or cabinet the head support is raised thereby. All these structures, however, leave exposed 25 to view the unsightly metal frame of the machine and its moving parts. In order to avoid this objection the frame has sometimes been completely inclosed in a cabinet, the front of which is hinged or otherwise connected 30 so that it may be opened when the machine is to be used for access to the treadle and other parts of the machine. Such cabinets, in order to fully conceal the machine, have been provided with floors or 35 bottoms, which not only catch dirt and refuse but necessitate pivoting the treadle higher up in the machine than is comfortable or convenient for working, and cabinets of this character have the further disadvantage 40 that they inclose the machine on three sides when in use and shut off ventilation thus increasing the discomfort of the operator. The advantage of a sewing machine cabinet which is open at the bottom or substantially 45 raised from the floor has been recognized, but the difficulty heretofore has been that, ordinarily, the treadle, if it is located low enough in the machine for the comfort and convenience of the operator, is 50 visible when the cabinet is closed. It has been proposed, in order to obviate this difficulty, to mount the treadle and the driving wheel of the machine in a vertically recipro-

cable frame which may be raised when the cabinet is closed and lowered for use when 55 the cabinet is open, this construction being combined with a support for the sewing machine head which may be lowered at the same time that the treadle and wheel are raised and raised when the latter are lowered. 60 This construction, however, is objectionable because of the weight of the movable parts and the consequent labor in moving them, and further because either the parts must be so closely fitted as to engender 65 considerable friction thereby increasing the difficulty of operating them, or else they rattle during the operation of the machine.

My invention provides a cabinet in which the legs and feet of the operator are substantially uninclosed when using the machine, in which the frame and mechanism including the treadle and head of the machine are entirely concealed when the cabinet is closed, so that there is no suggestion 75 of mechanism about the cabinet when closed, and in which during use the parts are most conveniently located. The machine is readily and with little effort opened up for use or closed when its use is finished, the 80 parts which it is necessary to move being light and so pivoted as to require little effort to shift them.

In the accompanying drawings I have shown and in the following specification described in detail a preferred form of my invention. It is to be understood, however, that the specific disclosure is for the purpose of exemplification only and that the scope of the invention is defined in the following claims in which I have endeavored to distinguish it from the prior art so far as known to me without, however, relinquishing or abandoning any portion or feature thereof.

In the accompanying drawings, Figure 1 is a perspective view of my invention showing the cabinet closed; Fig. 2 a plan view of the machine with the parts in the position which they occupy when the machine 100 is in use; Fig. 3 is a front elevation of the machine with the parts in the same position; Fig. 4 is a vertical transverse section on the line 4-4 of Fig. 3; Fig. 5 is a similar view of the upper portion of the machine 105 with the parts in the position which they

occupy when the machine is closed; Fig. 6 a horizontal section on line 6—6 of Fig. 5; Fig. 7 an enlarged section of a detail in line 7—7 of Fig. 2 and Fig. 8 a perspective 5 of a detail partly in dotted lines.

Each part is designated by the same reference character wherever it occurs throughout the several views.

The table top, cabinet and movable parts 10 of the machine are all mounted upon a stationary cast metal frame. This frame, in common with those of the prior art, comprises a pair of end frames 11, 12, connected by a suitable cross brace or strut 13 and 15 connected at their tops by the machine table top 14 which is screwed or otherwise secured thereto. The general outline of the end frames is rectangular to conform to the shape 20 of the cabinet, the back 15 and the stationary end walls 16 of which may be screwed or otherwise fastened thereto. The stationary end walls, however, extend only about half way forward of the top of the cabinet, the forward half of the machine being 25 closed by swinging walls as will presently appear. At their upper ends the end frames extend substantially the full depth of the table top as at 17, and the base of the end frames are of similar extent, but intermediate 30 at the top and base portions the end frames only extend about half way from the back of the machine or to the same extent as the stationary end walls, the purpose of which construction is that the operator may, if desired, sit with one foot outside the end frame 35 without being unnecessarily hampered thereby, which is sometimes convenient because of the location of the needle.

The inclosure of the cabinet is completed 40 by a pair of swinging members 19, 20, which are hinged as at 21 to the front edges of the stationary side walls and when closed in the position shown in Fig. 1 complete the respective end walls. A panel 22, 23, is rigidly connected to each of the swinging end 45 walls at right angles thereto and when the end walls are swung into the position shown in Fig. 1 said panels together form the front of the cabinet.

50 As shown more particularly in Fig. 4 the end frames are each formed with substantially straight vertical legs at the front and back, the back legs fitting in the corner between the rigid end walls and the back wall 55 of the cabinet, and the total depth of the end walls is such as to bring the front legs of the end frames accurately into the corners of the swinging doors composed of the swinging end walls and front panels. The 60 front legs are offset forwardly and outwardly and the rear legs rearwardly and outwardly as at 24, 24, to form housings for the casters 25, and the walls of the cabinet are provided at these corners with downward extensions forming legs which embrace 65

and conceal the metal legs of the frame and fit in over the shoulders formed by the 70 caster housings.

As heretofore stated the frame is provided with a drop head mechanism whereby when the machine is not in use the head is concealed in the cabinet, and this mechanism is substantially the same as that shown in my Patent 1,003,952, granted to me October 17, 1911, and therefore need not be described in detail here, except in so far as it is modified to adapt it for use in connection with the present invention. The table top is formed with a rectangular opening 26 to the forward edge of which the head support and drip pan 27 are hinged at 28, the head 75 of the machine being connected to the support in any suitable or well-known manner. A yoke or rock shaft 29 is pivoted at 30 in bearings in the respective end frames and connected by a pair of links 31 to the free edge of the head support in such manner that by swinging the yoke or cradle the head support is swung from the lowered position 80 shown in Fig. 5 to the raised position shown in Fig. 4 and vice-versa. For the purpose of swinging the yoke or cradle it is formed with a segment or sector 32 which is connected by a chain 33, see Fig. 4, with a link 34 which is in turn pivotally connected to the customary hinge-leaf 35. Said link, as shown more particularly in Fig. 7, is pivoted in a housing 36 let into a groove in the hinged edge of the leaf 35 and secured thereto by the flange 37. The housing forms a 85 complete lining for the groove in the hinged leaf and a bearing for the link 34 when the leaf is horizontal, as shown in Figs. 2 and 3. The table top is slotted in register with the groove in the hinged leaf, the slot 38 extending a sufficient distance inside the end frame of the machine to permit said link to move freely therethrough in swinging the leaf from open to closed position, and vice-versa, and the end frame is cast with an 90 outwardly extending lug or bracket 38' which is received into the lower part of the slot 38 and forms a rest or support for the link when the latter is in horizontal position. The free or swinging end of the link is slotted as at 39 and receives a clevis to which the chain 33 is attached. The segment on the yoke about the curved periphery of which the chain extends maintains the alignment of the chain during the swinging 95 of the yoke. By reason of the construction just described the swinging of the hinge-leaf from the closed position in which it constitutes a cover for the table top to the open position raises the head support and 100 head of the sewing machine. When in the open position the leaf is supported not only by its hinges and the link but also by the front section or door 22 of the cabinet which 105 in the open position extends beneath said 110 door. The head support is provided with a 115

leaf, as indicated in dotted lines in Fig. 2. In order that the machine head may swing through the opening in the table top the opening must be made larger than it is desirable to make a head support and in order to close the space between said head support and the rear edge of said opening an apron 40 is pivoted to the head support by metal straps 41 and supported in raised position

10 from the head support by the brackets 42. When lowered within the cabinet the apron takes the position shown in Fig. 5.

The driving wheel 43 of the machine, as shown in Figs. 3 and 4, is journaled on a stationary arbor 44 which is secured by the nut 45 to the spider or strut 13 connecting the side frames. Said driving wheel is, as usual, directly under the pulley 46 of the machine head and connected thereto by the strap 47 which extends through suitable openings provided in the head support and apron for the purpose. The guard 48 about the lower half of the driving wheel serves to maintain the strap in proper relation to 20 the driving wheel when the machine head is lowered.

In order that the treadle 49 may be in proper position for operation when the machine is opened up and may be entirely concealed within the cabinet when closed, notwithstanding the open construction of the lower portion of the same, I have devised the following construction. The treadle 49 is journaled at 50 in arms 51, 52, secured 30 respectively to the inner sides of the end frames at 53 (see Fig. 4). These arms are rectangular or L-shaped and when in the lower position shown in Fig. 4 the radial portions thereof are horizontal and masked 35 by the horizontal bars 54 of the side frames to which they are pivoted, and the downwardly turned extensions 55 of said arms which carry the treadle near their lower ends are formed with sockets 56 to receive 40 the horizontal bars 54 of the side frames to which they are pivoted, and the downwardly turned extensions 55 of said arms which carry the treadle near their lower ends are formed with sockets 56 to receive 45 the connecting bar 57 extending between the arms and constituting therewith a treadle supporting frame. At its rear right-hand corner the treadle is formed as usual with a laterally extending arm 58 which is bifurcated at 59 to receive the end of the 50 pitman 60 which is pivoted therein. The other end of the pitman is connected in any approved manner as at 61 to the driving wheel. When lowered into operating position 55 the arms of the treadle supporting frame are supported upon studs 62 projecting inwardly from the side frames.

In order that the treadle supporting frame may be raised at the same time and 60 by the same means by which the head support is lowered and vice-versa, a link 63 connects the arm 52 with a lug 64 upon the cradle or yoke 29, the lower end of said pitman or link being pivoted in a slot 65 in the arm 50. From an inspection of Fig.

4 it is obvious that as the yoke is swung downwardly to bring the head within the cabinet the treadle support is raised through the instrumentality just described. The movement of the yoke in a direction to conceal or lower the machine head is limited by an extension stop 66 formed upon the lug 64 coming in contact with a stationary part of the machine frame.

The parts above described are so designed 75 that when the treadle support is in raised position the pivots are just above the lower edge of the wall of the cabinet. It is necessary therefore in order that the treadle may not appear that it be substantially horizontal when in this position. With this object in view the weight of the driving wheel is reduced at 67 along the portion of its periphery adjacent the pivotal point of the pitman so that the weight of the latter is 80 so compensated for that the treadle will remain in the horizontal position when raised and therefore out of sight.

By pivoting the treadle support in the manner just described and connecting it to 90 the yoke it serves to substantially counter-balance the head in opening and closing the machine thereby reducing the effort required. Furthermore the construction is such because of the pivotal connection and 95 the stops employed that the device is substantially as rigid as though the treadle were pivoted directly in the end frames and thus rattle and vibration from this part of the construction is substantially eliminated. In my construction, further, the driving wheel is mounted directly on a stationary part of the frame and takes no part 100 in the vertical movement either of the treadle or of the sewing machine head thus 105 reducing the weight of parts to be shifted and minimizing the vibration and rattle of the machine.

I claim:

1. In a sewing machine, a main frame, a 110 cabinet surrounding the frame concealing the legs thereof but cut away intermediate the legs at its lower end, a swinging frame pivoted to the main frame above the cut-away portion of the cabinet on an axis 115 parallel to the front of the cabinet, a treadle pivoted on said swinging frame, a head movable on the main frame from a position within to a position without and above the cabinet and connections between said head 120 and the swinging frame whereby the raising of the head lowers the swinging frame.

2. In a sewing machine, a main frame, a cabinet surrounding the frame and concealing the legs thereof but cut away intermediate the legs at its lower end, a swinging frame pivoted to the main frame above the cut-away portion of the cabinet on an axis 125 parallel to the front of the cabinet, said swinging frame comprising a pair of down- 130

- wardly bent angular arms, stops on the main frame engaging said arms when the latter are in the lowered position, a treadle pivoted in the lower ends of said arms, a head movable on the main frame from a position within to a position without and above the cabinet, and connections between said head and swinging frame whereby when the head is raised the swinging frame is lowered.
- 16 3. In a sewing machine, a main frame, a cabinet surrounding the frame and concealing the legs thereof but cut away intermediate the legs at its lower end, a stationary journal on the main frame, a driving wheel mounted on the stationary journal, a swinging frame pivoted to the main frame above the cut-away portion of the cabinet on an axis parallel to the front of the cabinet, a treadle pivoted on said swinging frame, a head movable on the main frame from a position within to a position without and above the cabinet, and connections between said head and the swinging frame whereby the raising of the head lowers the swinging frame.
- 25 4. In a sewing machine, a main frame, a cabinet surrounding the frame and concealing the legs thereof, but cut away intermediate the legs at its lower end, a stationary bearing on said frame, a driving wheel journaled on the bearing, a sewing machine head pivotally mounted on the frame and adapted to be moved from a position within the frame to a position above the same and outside the cabinet, means for raising and lowering said head, a swinging frame pivoted to the main frame above the cut-away portion of the cabinet on an axis parallel to the front of the cabinet, a treadle pivoted on said swinging frame at the free end thereof, and connections between the sewing machine head and said frame whereby when the sewing machine head is in its upper position the treadle is lowered to operative position, and when the sewing machine head is in lowered position the treadle is held in a substantially horizontal position immediately above the cut-away portion of the cabinet.
- 50 5. In a sewing machine table, a swinging support for a sewing machine head, a driving wheel mounted on a stationary bearing, a swinging frame, a treadle journaled upon said swinging frame, a connection from said treadle to said driving wheel and connections comprising a link and an intermediate lever for simultaneously raising said head support and lowering said swinging frame.
- 60 6. In a sewing machine, a main frame, a swinging support for a sewing machine head, a driving wheel mounted on a stationary bearing, a swinging frame pivoted on a transverse axis within the main frame, a treadle journaled upon said swinging frame, a connection from said treadle to said driv-

ing wheel and connections comprising an intermediate link and lever for simultaneously raising said head support and lowering said swinging frame.

7. In a sewing machine, a stationary frame, a head adapted to be raised and lowered, a rock shaft journaled in the stationary frame, a connection between the head and rock shaft for raising the former, a treadle support consisting of a frame movable in a vertical plane, a treadle on said support, a driving wheel, a pitman connecting said treadle and driving wheel and a connection between said rock shaft and frame to raise and lower the treadle.

8. In a sewing machine table, a stationary frame, a pivoted head support, a swinging yoke journaled in the stationary frame, a connection between the head support and the swinging yoke for raising the former, a treadle support consisting of a swinging frame pivoted to the stationary frame, a treadle on said support, a driving wheel, a pitman connecting said treadle and driving wheel, and a connection between said swinging yoke and frame to raise and lower the treadle.

9. In a sewing machine table, a stationary frame, a swinging head support pivoted therein, a swinging yoke also journaled in said frame, links connecting said swinging yoke and head support, a treadle support consisting of a swinging frame pivoted in the stationary frame, a link connecting said treadle support and swinging yoke, a treadle on said support, a driving wheel mounted on a stationary bearing and a pitman connecting said driving wheel and treadle.

10. In a sewing machine table, front, side and end walls extending nearly to the floor, a movable frame, means for raising and lowering said frame, a treadle pivoted in said frame and adapted to be raised and lowered therewith, a driving wheel, a connection between the driving wheel and treadle, the movable system comprising the treadle, driving wheel and connection being so weighted as to always maintain the treadle in a position in which it is substantially concealed by the walls of the table.

11. In a sewing machine table, a swinging frame, means for raising and lowering said swinging frame, a treadle pivoted in said frame and adapted to be raised and lowered therewith, a driving wheel, a connection between the driving wheel and treadle, the movable system comprising the treadle, driving wheel and connection being so weighted as to always maintain the treadle when at rest in a substantially horizontal position.

12. In a sewing machine table, a movable frame, means for raising and lowering said frame, a treadle pivoted in said frame and adapted to be raised and lowered therewith, a driving wheel, a connection between the

- driving wheel and treadle, the wheel being so counterweighted as to maintain the treadle substantially level when at rest.
13. In a sewing machine table, a frame comprising end frames having front and rear legs, a cabinet adapted and arranged to inclose said frame comprising pivoted end walls and doors for closing the opening in the cabinet front between said end walls, the front legs fitting respectively in the corners between the corresponding end wall and door when the cabinet is closed and bracing the same.
14. In a sewing machine table, a rigid frame comprising an end frame having a front leg, a cabinet secured to said frame and adapted to inclose the same, comprising pivoted side walls and doors for closing the front of the cabinet attached to said side walls, said leg fitting in the corners between the corresponding wall and door when the cabinet is closed and bracing the same.
15. In a sewing machine table, a frame comprising a pair of end frames each having a substantially vertical front leg, an open bottom cabinet secured to said frame and adapted to inclose the same comprising walls, the intermediate portions of which terminate at substantial distances short of the lower ends of said leg and which are extended at the corners to substantially mask said legs.
16. In a sewing machine table, a rigid frame having legs at the corners thereof, a cabinet secured to said frame and inclosing the same, the walls whereof at their intermediate portions terminate a material distance above the lower ends of said legs and which are extended at the corners of said cabinet to mask said legs.
17. In a sewing machine table, a rigid frame comprising a pair of end frames, each having a front leg, a cabinet secured to said frame and adapted to inclose the same and comprising a stationary back, pivoted side walls and doors for closing the front of the cabinet rigidly attached to said side walls perpendicularly thereto, the front legs respectively fitting into the angles between the side walls and doors and bracing the same.
18. In a sewing machine table, a rigid
- frame comprising a pair of end frames, each having a leg, an offset caster support connected to said leg and forming a shoulder with respect thereto, a cabinet attached to said frame comprising a stationary back and a pivoted wall, legs upon the wall adapted when said walls are closed to overhang the shoulders on the frame legs and sections supported on said end walls for closing the front of the cabinet.
19. In a sewing machine table, a frame formed with front and rear legs, a cabinet inclosing said frame comprising a pair of stationary walls, a pair of pivoted walls, said walls terminating a material distance short of the ends of said legs at their intermediate portions and extended at the corners of said cabinet to conceal said legs.
20. In a sewing machine table, a pair of end frames formed with forwardly projecting legs, a cabinet for inclosing said frame comprising a stationary back, a pair of stationary end walls, a pair of pivoted end walls, a front section rigid with each end wall and legs formed on said end walls and front sections adapted to inclose the legs on the stationary frame upon two sides thereof.
21. In a sewing machine table, a stationary frame, a frame pivoted therein, means for raising and lowering the pivoted frame, a treadle mounted on the pivoted frame, a driving wheel, a driving connection between the driving wheel and treadle, the system comprising the treadle connection and driving wheel being so weighted as to normally bring the treadle to rest in a predetermined position and an open bottom cabinet surrounding said frame and adapted to inclose the same.
22. In a sewing machine table, a rectangular frame, a top on said frame, a cabinet inclosing the frame comprising stationary side walls, swinging side walls hinged to said stationary walls and front sections rigidly secured to said swinging walls, the vertical corners of the cabinet engaging and braced by the frame.
